UNITED STATES PATENT OFFICE.

LUCIUS W. WOOSTER, OF GIBBSBOROUGH, NEW JERSEY.

COMBINED DUMB-BELL, CLUB, AND EXERCISING DEVICE.

SPECIFICATION forming part of Letters Patent No. 506,894, dated October 17, 1893.

Application filed December 3, 1892. Serial No. 453,967. (No model.)

To all whom it may concern:

Be it known that I, LUCIUS W. WOOSTER, a citizen of the United States, residing at Gibbsborough, in the county of Camden, State 5 of New Jersey, have invented a new and useful Improvement in a Combined Dumb-Bell, Club, and Exercising Device, which improvement is fully set forth in the following specification and accompanying drawings.

10 My invention consists first of a dumb bell having a hollow head which contains a spring for exercising purposes, means in the head whereby the bell may be adjustably weighted, a novel connected handle, and means for preventing crushing-in of the head.

15 Figure 1 represents a partial longitudinal section of a combined dumb bell, club and exercising device embodying my invention. Figs. 2 and 3 represent transverse sections 20 thereof, respectively on lines x, x , and y, y , Fig. 1.

Similar letters of reference indicate corresponding parts in the several figures.

Referring to the drawings: A designates a 25 dumb bell formed of the hollow heads B, B, and the connecting grip or handle C.

D designates a rod which is passed through the heads B and handle C, and has on one end the nut D', and on the other end the handle 30 E. Within the heads are the sleeves F, through which the rod D extends, said sleeves being encircled by either the concentric rings G or the box H, the latter having its hub J on the reduced portion K of the sleeve, said box 35 containing a coiled spring L, one end of which is secured to the sleeve F, and the other end to the periphery of the box, it being noticed that as the nut D' is tightened, the sleeve is 40 pressed firmly against the opposite side of the head B, and thus held immovable, the sleeves furthermore preventing crushing-in of the heads, especially at the centers thereof. Encircling the box H is a strap or cord M, one end of which passes through an opening N in 45 the periphery of the head, and has an eye or ring P connected with it, whereby it may be connected with a wall, ceiling, &c., and when the dumb bell is grasped and drawn back, the 50 spring may be wound up, and as the dumb bell is moved toward the wall, ceiling, &c., the

spring unwinds, or vice versa, thus providing a convenient and effective exercising device. Each head may be provided with a spring and operative parts, but when desired the same may be removed, and each head supplied with rings G, thus weighting said head, the number of rings employed being in accordance with the adjusted weight that it is desired to impart to the dumb bell. When the dumb bell as such is to be used, the handle E is removed, but when said handle is applied to one of the heads, as shown in Fig. 1, it is evident I produce a club of the order of an Indian club for exercising purposes, the dumb bell constituting the head of the club. 55

The heads are hollow as has been stated, and they are fitted together on their peripheries, where one section is provided with a tongue Q, which enters a groove in the other section, thus interlocking the sections at their 60 peripheries and preventing rotation of the same, while their separation is prevented by the rod D. When the nut D' is unscrewed, the sections of the heads may be separated and access had to the interior of the same for 65 removal or application of the spring or weight in either head or both heads as desired or required. A washer R is interposed between the hub J of the spring-containing box H, and the adjacent wall of the head B, so that the 70 box is set out from the latter.

When the handle E is removed, a nut may be substituted therefor, so that the rod is retained in position for connecting the parts of the dumb bell.

Having thus described my invention, what I claim as new, and desire to secure by Letters Patent, is—

1. A combined dumb bell and exercising device consisting of a dumb bell having a grip 75 between the heads thereof one head being hollow and having a sleeve therein, a rod passing through said sleeve and head, a box on said head, a spring connected with said sleeve and box, a cord around said box passing through an opening in said head, and an eye on the outer end of said cord, said parts being combined substantially as described.

2. A dumb bell having a hollow head formed in sections, a sleeve in said head, and a con-

necting rod passing through the walls of said head, and through the sleeve and the grip of the dumb bell, thus coupling the head and grip, the sleeve preventing crushing in of the center of the heads, the periphery of the sections being provided respectively with a tongue and groove, all substantially as described.

3. A dumb bell having hollow heads, a grip intermediate of said heads, and a connecting rod passing through said heads and grip, in combination with a box, a sleeve in said box, a spring connected with said sleeve and box,

a cord around said box, a rod passing through the heads, the grip and sleeve, and a handle connected with the projecting end of the rod, thus coupling the sections of the head and grip and attaching the handle to one of the heads, the sleeve preventing crushing in of the sectional head when the parts are coupled, all substantially as described.

LUCIUS W. WOOSTER.
